[57] CLAIM

The ornamental design for an electrified vacuum hose
for a wet/dry vacuum cleaner, as shown and described.

DESCRIPTION

FIG. 1 is a right side elevational view of an electrified
vacuum hose for a wet/dry vacuum cleaner showing
our new design;

FIG. 2 is a bottom plan view thereof;

FIG. 3 is a top plan view thereof;

FIG. 4 is a front elevational view thereof; and

FIG. 5 is a rear elevational view thereof.
